BAR AND HOLDER FOR LAUNDRY
MARKERS

Angus F. Hanney, Norwood, Ohio, assignor to
The American Laundry Machinery Company,
Norwood, Cincinnati, Ohio, a corporation of
Ohio

Application March 20, 1930. Serial No. 437,626

5 Claims. (Cl. 40—19.5)

My invention relates to key and storage bars for laundry marking clips and magazines for clip laden key or storage bars. It relates, particularly, to a key or storage bar adapted to receive 5 only marking clips for one particular class of goods and a magazine adapted to receive only clip laden key bars that bear such particular type of marking clip.

As is well known in the laundry art, separate 10 pieces of goods in each bundle are identified by metal marking clips attached thereto. These clips are made in groups, each group consisting of a predetermined number of exact duplicates adapted to fit on a given key or storage bar provided therefor, the marking clips being such as to fit on that key bar only. Further it is well known in the art that different marking clips are provided for goods in the flat work class and goods 15 in the wearing apparel class and these clips are attached to their respective type of goods at different points.

One object of my invention is to provide a key bar and magazine for a clip laden key bar which, when the key bar and magazine are in assembled 20 relation, will permit the removal of only one clip from the key bar at a time.

Another object of my invention is to provide a key bar and magazine for a clip laden bar wherein means are provided for preventing the 25 use of any but a key bar having clips thereon of a given group, in combination with a given magazine.

Still another object of my invention is to provide a lock for preventing accidental separation of 30 a clip laden key bar from its cooperating magazine and to provide an inexpensive durable and relatively simple device.

Other objects of my invention may be seen in the following description and one embodiment 35 thereof may be seen in the accompanying drawing wherein similar characters of reference designate corresponding parts, and wherein:

Fig. 1 is a front elevation of a key or storage bar having marking clips thereon and a magazine 40 in assembled relation; Fig. 2 is a view partly in section and partly in elevation taken on the line 2—2 of Fig. 1; Fig. 3 is a view of the opposite side of the device shown in Fig. 1; Fig. 4 is a fragmentary elevation of the magazine showing one 45 form of bar holding element; Fig. 5 is a view similar to Fig. 4 but showing a slightly different method of holding the bar in cooperative relation with the magazine; Fig. 6 is an elevation of one end of a key bar which is adapted to cooperate 50 with the magazine shown in Fig. 4; Fig. 7 is a

view similar to Fig. 6 but showing a key bar adapted to cooperate with the magazine shown in Fig. 5; and Fig. 8 is a sectional view taken on the line 8—8 of Fig. 1.

Referring to the drawing, I have shown my invention as comprising a storage bar 10, that is of the proper length to accommodate a given number of marking clips of the type disclosed in the patent to Lane, No. 1,621,259. As shown, it also embodies a magazine 11 that is adapted to 60 receive a clip laden storage bar 10, as shown in Fig. 1 and is provided with means whereby the clip laden storage bar may be secured therein. Such magazine also embodies means such as to permit only one marking clip at a time from 65 being removed from the storage bar when the bar is disposed within the magazine.

A storage bar 10 is, in this instance, provided with a plurality of laterally extending wards or lugs 12 adjacent its lowermost end, these wards 70 or lugs, being of such contour that only members of a particular group of marking clips may be placed on the bar. However, it will be understood, that any other suitable means, such, for instance, as making the storage bars of different 75 shapes, may be used to prevent only members of a given group of clips from being placed on the bar.

Intermediate its ends and more or less adjacent the upper end of the storage bar is provided 80 a laterally extending stop 13 against which the uppermost marking clip abuts when the storage bar is completely filled with clips, and which provides a means for preventing more than a 85 given number of clips from being disposed on the bar. Such bar is also provided adjacent its uppermost end with wards that, in this instance, take the form of openings 14, the purpose of which will be hereinafter apparent.

The magazine 11 is preferably substantially rectangular in cross section and trough-shaped, having a base or bottom wall, side walls, and an open side as shown at 15 in Figs. 4 and 5 and by dotted lines in Fig. 3, and is provided adjacent its uppermost end with pins or wardings 16 extending outwardly from the inner side of the rear wall thereof, the pins being such as to interfit with the openings 14 in the storage bar 10, as shown in Fig. 2. As also shown in this Figure, the magazine 11 is provided with a substantially U-shaped gravity locking device 17 having a slot 18 in one leg thereof adapted to slide upon a pin 19 disposed on the outer surface of the magazine rear wall and the other leg extends downwardly 100 in front of the outermost ends of the pins 16. 110

Therefore, as shown in Fig. 2, when the storage bar 10 is disposed on the pins 16 and the lock 17 is permitted to gravitate to its lowermost position, the storage bar 10 will be securely locked 5 on the pins.

Also, the magazine 11 is provided on its lowermost end with shelves 20 on which the lowermost clip from the storage bar 10 is adapted to rest, the shelves being disposed at such distance from 10 the lower end of the storage bar that, when a clip is resting thereon, other clips will be prevented from sliding off the storage bar. On the same plane of the shelves 20, one wall of the magazine is provided with an aperture 21 large enough to 15 permit a marking clip to be moved therethrough and a slot 22 is formed between the shelves 20 and the opposite side walls of the magazine for the purpose of permitting a suitable pusher apparatus to pass therethrough and remove the 20 lowermost clip from the magazine. Suitable lugs 23 are provided at the front of the magazine to act as shields and prevent the lowermost marking clips from moving laterally out of the 25 magazine.

In order to facilitate placing a clip laden storage bar within the magazine 11 or to remove it therefrom, the magazine is mounted on and adapted to be swung about a pivot 24 adjacent its lower end, which pivot is supported on the 30 upper end of a bracket 25 secured to a table or other supporting means. A spring 26, that is sufficiently strong to retain the magazine 11 in its normal upright position but is not sufficiently strong to lift the magazine from a horizontal or 35 angular position, is provided at the pivot 24 with one end thereof bearing against the surface of the magazine and the other end bearing against the outer surface of the bracket 25.

In the operation of this device, the magazine 40 11 is swung about its pivot to the desired angular or horizontal position, the gravity lock 17 is moved so that the one leg thereof will not be in front of an extreme end of the pins 16, and a clip laden storage bar 10 is placed in the magazine through the open side thereof with the 45 openings 14 cooperating with the pins 16 whereupon the magazine 11 is swung to its normal vertical position, the lock 17 gravitating to a position to prevent removal of the storage bar 50 from the pin 16. Then the lower end of the storage bar being in the position shown, successive single marking clips may be removed from the lower end of the magazine in any desired manner, through the gateway or openings 21.

In order to provide storage bars adapted for 55 use with marking clips of different set groups, storage bars 10 having different sized or a different number of openings adjacent the upper end thereof that are adapted to cooperate with 60 different sized or a different number of pins 16 adjacent the upper end of the magazine, are provided. For instance, as shown in Figs. 4 and 6, the storage bar 10 has a plurality of relatively small openings 14 and the magazine 11 has a 65 plurality of pins 16 adapted to fit with such openings, while, as shown in Figs. 5 and 7, the storage bar 10 has a relatively large single opening and the magazine 11 has a single pin adapted to interfit with such opening. With such provisions, even though the marking clips of groups 70 belonging to different sets could be disposed on the same storage bar, such bar could not be used except with a magazine adapted for use with that particular class of goods. Thus, a double check 75 is provided to prevent error in the application

of marking clips to laundry goods of different classes.

It will be seen that I have provided a combination of parts, namely, a storage bar and a magazine therefor, embodying numerous advantageous features. For instance, a device is provided whereby only single marking clips can be successively removed from the device making it particularly applicable to automatic or mechanical marking clip attaching apparatus. At the same time, a storage bar is provided on which marking clips may be readily placed together with a magazine in which the clip laden storage bar may be readily placed or from which it may be as readily removed. 80 85 90

What I claim is:

1. Apparatus of the class described, comprising, in combination, a marking clip storage bar including a rigid length of material of a contour to receive a plurality of clips of one group only, and a pivotally mounted magazine for receiving clip laden storage bars and movable to either operative or inoperative position, wardings on said magazine and clip storage bars whereby the bars that may be operatively disposed with 100 in said magazine are limited to like bars, means for locking a storage bar within said magazine, and yielding means tending to maintain said pivotally mounted magazine in one of its positions and yieldingly resist rotation of said magazine about its pivotal mounting.

2. Apparatus of the class described, comprising a plurality of magazines, each adapted to operatively receive single key bars of a given group, and a group of tag holding key bars for each magazine, the bars of each group being differently warded for different sets of tags, each magazine having releasable interlock means to coact with means on any bar of its group to connect such bar to such magazine, the coacting means on all 115 of the bars of one group being identical but different from the coacting means of the bars of all other groups.

3. Apparatus of the class described, comprising a magazine of elongated trough-like form having its base or bottom wall near one end provided with a projection, a warded tag receiving key bar adapted for insertion into said magazine and having an opening to receive said projection, and a locking member slidably mounted on the magazine and having a portion adapted to be moved into or away from a position opposite the end of said projection to releasably confine the key bar thereon. 120 125 130

4. Apparatus of the class described, comprising a magazine of elongated trough-like form having its base or bottom wall provided with a projection near the upper end thereof, a warded tag receiving key bar adapted for insertion into said magazine and having an opening to receive 135 said projection, a locking member slidably mounted on the magazine and having a portion adapted to be moved into or away from a position opposite the end of said projection to releasably confine the key bar thereon, shields partly closing 140 the end of said trough-like magazine opposite from the end having the projection thereon, and a gate-way through which clips can be removed from said magazine, said shields being so arranged as to prevent removal of tags from said 145 magazine except through said gateway.

5. Apparatus of the class described, comprising a magazine of elongated trough-like form having its base or bottom wall provided with a projection near the upper end thereof, a warded 150

tag receiving key bar adapted for insertion into said magazine and having an opening to receive said projection, a locking member slidably mounted on the magazine and having a portion 5 adapted to be moved into or away from a position opposite the end of said projection to releasably confine the key bar thereon, shields partially closing the end of said trough-like magazine opposite from the end having the projection 10 thereon, and a gateway through which chips

can be removed from said magazine, said shields being so arranged as to prevent removal of tags from said magazine except through said gateway, and said magazine being pivotally mounted and provided with resilient 30 means tending to maintain said magazine in a predetermined position and yieldingly resist movement thereof about its pivotal mounting.

CERTIFICATE OF CORRECTION.

Patent No. 1,929,974.

October 10, 1933.

ANGUS F. HANNEY.

It is hereby certified that error appears in the printed specification of the above numbered patent requiring correction as follows: Page 1, line 91, for "adacent" read adjacent; page 3, line 10, claim 5, for "chips" read clips; and that the said Letters Patent should be read with these corrections therein that the same may conform to the record of the case in the Patent Office.

Signed and sealed this 5th day of December, A. D. 1933.

R. M. Hopkins
